**PREVENTING SILICA BAKE-ON DEPOSITS FROM
SILICATE DETERGENT COMPOSITION**

U.S. CL. 252—135

4 Claims

This invention relates to a new detergent composition and a process for preventing the deposition of opaque deposits on articles washed therewith. More specifically, it deals with silicated detergent compositions highly useful in automatic dishwashing machines, whereby the deposition of opaque films and dense white spotted areas on the articles being washed is prevented.

Detergent compositions used in mechanical dishwashing machines usually comprise in combination an alkaline detergent salt, e.g., sodium metasilicate, an alkaline condensed phosphate, e.g., sodium tripolyphosphate, and an alkaline carbonate, e.g., sodium carbonate.

Clear transparent drinking glasses washed with the above described composition oftentimes exhibit an opaque film and dense white spotted areas where the detergent has baked onto the glass. Aluminum pots and pans also exhibit unsightly white streaks when washed in silicate containing detergents. It has been found that these deposits are caused by the silicate present in the detergent. These silicates however are essential ingredients of alkaline detergent compositions because of their excellent anticorrosive and detergent qualities.

It is therefore an object of the instant invention to produce a silicated detergent composition which will not cause streaks, films or deposits on articles being washed therewith.

Another object of the instant invention is to set forth a process for preventing silicated detergent compositions from depositing films, streaks or spotted areas on the articles being washed.

A further object of the instant invention is to set forth a process of preventing silicate containing detergent compositions for dishwashing machines from depositing films, streaks, or spots on the articles being washed, by means of adding to the composition boric acid and/or its alkali metal salts in prescribed amounts.

A still further object of the instant invention is to set

2

forth a new detergent composition containing a crystalline silicate and an amount of boric acid and/or a borate salt sufficient to form a calculated disilicate when the mixture is dissolved in water.

Other objects and advantages of the instant invention will become more apparent from the following detailed description and examples.

As stated above it has been found that these deposits on glasses and pots and pans, etc., washed with detergent compositions in automatic dishwashing machines are a result of the silicate contained in the detergent. In evaluating the bake-on characteristics of the alkaline detergent salts, the following procedure was used showing both their singular and blended effect.

Procedure for evaluating detergent bake-on

Weigh 0.525 gram of detergent salt or detergent blends on the analytical balance and dissolve in 100 milliliters of distilled water. With an eye dropper, transfer ten drops of solution to a clean 70 mm. Pyrex watch glass. Place watch glass over an empty 250 ml. beaker and then place both into an oven for 30 minutes at 210° F. Allow to cool five minutes. Then rinse residue with a stream of distilled water from a 7 mm. glass tubing for 30 seconds. Place Pyrex watch glass and beaker into the oven for 15 minutes to dry. Examine for "bake-on" residue.

The detergent salts or blends thereof in the aforementioned formula, were evaluated singly and in combination by the "bake-on" test, the result of which are shown in Table I.

TABLE I

Detergent Salt	Appearance Before Rinsing	Appearance After Rinsing
Sodium tripolyphosphate	White residue	Clear.
Sodium carbonate	do	do
Sodium metasilicate, anhydrous	do	White residue.
Sodium carbonate, 28 parts	do	Clear.
Sodium tripolyphosphate, 46 parts	do	White residue.
Sodium carbonate, 28 parts	do	White residue.
Sodium metasilicate, anhydrous, 22 parts	do	White residue.
Sodium tripolyphosphate, 46 parts	do	do
Sodium metasilicate, 22 parts	do	do
Sodium carbonate, 28 parts	do	do
Sodium metasilicate, anhydrous, 22 parts	do	do
Sodium tripolyphosphate, 46 parts	do	do

From the above table it is apparent that sodium metasilicate cannot be easily rinsed from glass after "bake-on." The $\text{Na}_2\text{O}/\text{SiO}_2$ ratio of crystalline silicates extends from sodium orthosilicate ($\text{Na}_2\text{O}/\text{SiO}_2=2/1$) through sodium metasilicate ($\text{Na}_2\text{O}/\text{SiO}_2=1/1$) to colloidal sodium disilicate ($\text{Na}_2\text{O}/\text{SiO}_2=1/2$). Silicates of $\text{Na}_2\text{O}/\text{SiO}_2$ ratios between 1/1 and 1/2 are actually mixtures of crystalline sodium metasilicate and colloidal sodium disilicate and will be considered part of this invention.

I have discovered that the bake-on characteristics of crystalline silicates, when admixed with a calculated amount of boric acid and/or its alkali metal salts, will not only be altered but can be completely prevented.

The following examples were prepared and tested to determine the exact mole ratios of borate to silicate necessary to prevent deposits. These are disclosed in Table II.

TABLE II

Sodium metasilicate ($\text{Na}_2\text{O}\cdot\text{SiO}_2$) admixed with boric acid and various alkali metal borates. Total concentration 0.525%.

Boron Salt	$\text{Na}_2\text{O}/\text{B}_2\text{O}_3$	Mole ratio metasilicate/ boron salt	Appearance after rinsing
Boric acid, H_3BO_3	0/1	1/1	Clear.
Potassium pentaborate, $\text{K}_2\text{B}_5\text{O}_7\cdot 3\text{B}_2\text{O}_5\cdot 8\text{H}_2\text{O}$	0.2/1	8/1	Do.
Sodium tetraborate, $\text{Na}_2\text{B}_4\text{O}_7\cdot 5\text{H}_2\text{O}$	0.5/1	1/1	Do.
Do	0.5/1	2/1	Do.
Do	0.5/1	3/1	Opaque White.
Sodium metaborate, $\text{Na}_2\text{B}_3\text{O}_5\cdot 8\text{H}_2\text{O}$	1/1	1/1	Do.
Do	1/1	1/2	Do.
Potassium tetraborate, $\text{K}_2\text{B}_4\text{O}_7\cdot 4\text{H}_2\text{O}$	0.5/1	2/1	Clear.

The mole ratios of boron containing compounds to silicate compounds were calculated in accordance with the following equations:

- (1) $2(\text{Na}_2\text{OSiO}_2) + 2\text{H}_3\text{BO}_3 \rightarrow 2\text{NaBO}_2 + \text{Na}_2\text{O} \cdot 2\text{SiO}_2 + 3\text{H}_2\text{O}$
- (2) $8(\text{Na}_2\text{OSiO}_2) + \text{K}_2\text{B}_4\text{O}_7 \cdot 3\text{B}_2\text{O}_3 \cdot 8\text{H}_2\text{O} \rightarrow 8\text{NaBO}_2 + 2\text{KBO}_2 + 4(\text{Na}_2\text{O} \cdot 2\text{SiO}_2) + 8\text{H}_2\text{O}$
- (3) $2(\text{Na}_2\text{OSiO}_2) + \text{Na}_2\text{B}_4\text{O}_7 \cdot 5\text{H}_2\text{O} \rightarrow 4\text{NaBO}_2 + \text{Na}_2\text{O} \cdot 2\text{SiO}_2 + 5\text{H}_2\text{O}$
- (4) $2(\text{Na}_2\text{OSiO}_2) + \text{K}_2\text{B}_4\text{O}_7 \cdot 4\text{H}_2\text{O} \rightarrow 2\text{NaBO}_2 + 2\text{KBO}_2 + \text{Na}_2\text{O} \cdot 2\text{SiO}_2 + 4\text{H}_2\text{O}$
- (5) $2\text{Na}_2\text{B}_2\text{O}_4 \cdot 8\text{H}_2\text{O} + 2\text{NaH}_2\text{PO}_4 \rightarrow \text{Na}_2\text{B}_4\text{O}_7 + 2\text{Na}_2\text{HPO}_4 + 17\text{H}_2\text{O}$

Equation 3 and the results in Table II clearly illustrate that two moles of sodium metasilicate can be blended with one mole of sodium tetraborate before the critical mole ratio is exceeded. A 1/1 mole ratio of sodium metasilicate to sodium tetraborate produced a clear appearance showing that an excess of borate salt is not critical in preventing silica bake on. A 3/1 mole ratio of sodium

I have found that the boron salts listed in Table II and in Example I which includes the entire range from boric acid to metaborate ($\text{Na}_2\text{O}/\text{B}_2\text{O}_3$ from 0/1 to 1/1) are equally effective in preventing the undesirable silica bake-on of crystalline silicates over the complete $\text{Na}_2\text{O}/\text{SiO}_2$ span of 2/1 to 1/2.

Tests were also made of sodium orthosilicate
($2\text{Na}_2\text{O} \cdot \text{SiO}_2$)

10 having a $\text{Na}_2\text{O}/\text{SiO}_2$ ratio of 2/1, sodium sesquisilicate ($3\text{Na}_2\text{O} \cdot 2\text{SiO}_2 \cdot 11\text{H}_2\text{O}$) having a $\text{Na}_2\text{O}/\text{SiO}_2$ ratio of 3/2, and sodium silicate liquid ($\text{Na}_2\text{O} \cdot 1 \cdot 6\text{SiO}_2$) having a $\text{Na}_2\text{O}/\text{SiO}_2$ ratio of 1/1.6 both alone and with boron salts listed in Table II. Without the boron salts these three silicates produced a difficult to remove white silica bake-on.

15 When mixed with the boron salts in accordance with Equations 7 through 15, a clear appearance was produced after rinsing in the silica bake-on evaluation tests. Table II lists the various maximum silicate/boron ratios tested. Sodium metasilicate is shown for comparison.

TABLE III
[Silicate/Boron Ratios]

	Sodium Orthosilicate	Sodium Sesquisilicate	Sodium Metasilicate	Liquid Sodium Silicate
Boric acid, H_3BO_3	1/3	1/4	1/1	5/2
Potassium pentaborate, $\text{K}_2\text{B}_4\text{O}_7 \cdot 3\text{B}_2\text{O}_3 \cdot 8\text{H}_2\text{O}$	8/3	2/1	8/1	20/1
Sodium tetraborate, $\text{Na}_2\text{B}_4\text{O}_7 \cdot 5\text{H}_2\text{O}$	2/3	1/2	2/1	5/1
Potassium tetraborate, $\text{K}_2\text{B}_4\text{O}_7 \cdot 4\text{H}_2\text{O}$	2/3	1/2	2/1	5/1
1 Sodium metaborate, $\text{Na}_2\text{B}_2\text{O}_4 \cdot 8\text{H}_2\text{O}$	1/3	1/4	1/1	5/2

1 For each mole of sodium metaborate used, a mole of sodium dihydrogen phosphate was jointly used.

metasilicate to sodium tetraborate produced an opaque white film, indicating that an insufficient amount of borate salt was present to prevent silica bake-on.

As seen in Table II, sodium metaborate did not prevent the silica bake-on in any mole ratio tested. This can be remedied by acidifying the sodium metaborate with an acid salt and simultaneously blending with sodium metasilicate.

As shown in Equation 5, when two moles of sodium metaborate are acidified by two moles of monosodium dihydrogen phosphate, one mole of sodium tetraborate is formed. Therefore a mixture as shown in Example I below of two moles of sodium metaborate, two moles of sodium dihydrogen phosphate and two moles of sodium metasilicate did produce a clear appearance after rinsing in the silica bake-on evaluation test.

EXAMPLE I

Moles

Sodium metaborate ($\text{Na}_2\text{B}_2\text{O}_4 \cdot 8\text{H}_2\text{O}$) 2
Sodium dihydrogen phosphate ($\text{NaH}_2\text{PO}_4 \cdot \text{H}_2\text{O}$) 2
Sodium metasilicate (Na_2OSiO_2) 2

In order to show that the acid phosphate salt such as that used in Example I, did not in itself prevent silica bake-on, tests were made on a mixture of sodium metasilicate and sodium dihydrogen phosphate in the absence of boron salts in accordance with Equation 6 below. This mixture did not prevent a silica bake-on when tested in accordance with the silica bake-on evaluation test used above.

These acid phosphate salts (sodium dihydrogen phosphate, disodium phosphate and trisodium phosphate) were then tested alone and in admixture (1/1 mole mixture of disodium phosphate and trisodium phosphate). All produced a clear appearance when tested for bake-on in the absence of sodium metasilicate.

The equations used for preparing Table III are as follows:

70 In all of the above tests only the sodium salt is illustrated. It is possible, however, to use any of the alkali metal salts. To further illustrate this the following tests were made with potassium borates in accordance with the same ratios as shown by Equations 1 through 6. These tests are illustrated in Table IV which shows that the potassium

metasilicate also produces a white residue as does the sodium metasilicate and this silica bake-on or residue is prevented by the use of either potassium borate or sodium borate salts.

TABLE IV

Detergent Salt	Silica Bake-on Result
Potassium metasilicate ($K_2O \cdot SiO_2$) 2 moles	Clear appearance.
Potassium tetraborate ($K_2B_4O_7 \cdot 4H_2O$) 1 mole	Do.
Potassium metasilicate ($K_2O \cdot SiO_2$) 2 moles	Do.
Sodium tetraborate ($Na_2B_4O_7 \cdot 5H_2O$) 1 mole	Do.
Potassium metasilicate ($K_2O \cdot SiO_2$)	White residue.

The following examples set forth detergent compositions containing the prescribed ratios of boron containing compounds. Example A is a detergent composition for soft water and Example B discloses a typical detergent composition for both soft and hard water.

Example A.—Soft water

A detergent composition was prepared by blending for ten minutes in a ribbon mixer comprising by weight 10 parts of anhydrous trisodium phosphate, 48.2 parts of sodium tetraborate 5 mole hydrate, and 36.8 parts of anhydrous sodium metasilicate. To the mixture of alkaline detergent salts was dispersed 3 parts of a liquid low foaming nonionic surfactant followed by 2 parts of an organic chlorine releasing chemical as potassium dichloroisocyanurate. The final mixture was evaluated for bake-on using a Pyrex watch glass and also an aluminum evaporating dish as commonly used in a commercial laboratory. No silica bake-on was observed on either glass or aluminum when the detergent mixture was evaluated in soft water. However, an opaque white residue was observed on both aluminum and glass when the detergent mixture was evaluated in hard water from the tap of 17.1 grains hardness calculated as $CaCO_3$. It is apparent that the detergent composition of Example A is suitable for use in soft water but does not produce the desired result in hard water. This defect is easily overcome by using a water soluble phosphate, e.g., tripolyphosphate, or an organic sequestrant having sequestering capacity for the calcium and magnesium present in hard water. The method is described in the following example.

Example B.—Both soft and hard water

A detergent composition was prepared by blending in a ribbon mixer comprising by weight 46 parts of sodium tripolyphosphate-light density to which 3 parts of a low foaming nonionic surfactant was dispersed, followed by 27 parts (0.0927 mole) of sodium tetraborate, 5 mole hydrate and 22 parts (0.1803 mole) of anhydrous sodium metasilicate. Finally, 2 parts of potassium dichloroisocyanurate was added and the entire mixture made uniform by an additional 5 minutes blending. This particular composition produced a clear appearance on both glass and aluminum in both soft and hard water (17.1 grains) when evaluated by the silica bake-on test. The mole ratio of sodium metasilicate to sodium tetraborate is 1.94/1, since a slight excess of the latter is present.

A liquid composition was prepared containing only potassium salts according to the following equations:

Example C

The ingredients were added and mixed with an agitator in the order shown.

Parts by weight

Soft water	27.5
Tetra potassium pyrophosphate	22.5
Liquid caustic potash (50%)	12.55
Liquid potassium silicate (27.3%)	23.2
($K_2O/SiO_2 = 1/2.5$)	23.2
Potassium tetraborate ($K_2B_4O_7 \cdot 4H_2O$)	14.25

100.00 75

A clear liquid resulted and when tested at 1.05% concentration on glass and aluminum by bake-on test, a clear appearance resulted.

It is apparent from the foregoing that there is provided a new detergent composition which will not cause streaks, films or deposits on articles washed therewith and a process for preventing such undesirable characteristics in silicate containing detergents, by means of including in or adding to such detergent compositions boric acid or alkali metal borates in sufficient amount to form a calcuated disilicate when the mixture is dissolved in water. It is further apparent from the above that the boron containing compound may be any compound having a Na_2O/B_2O_3 range of 0/1 to 1/1. It is also possible for the composition to be used as a steam cleaning compound.

As this invention may be embodied in several forms without departing from the spirit or essential characteristics thereof, the present embodiment is therefore illustrative and not restrictive, and since the scope of the invention is defined by the appended claims, all changes that fall within the metes and bounds of the claims or that form their functional as well as conjointly cooperative equivalents are therefore intended to be embraced by those claims.

I claim:

1. A method of preventing silica bake-on deposits from mechanical dishwashing machine detergents containing alkali metal silicates wherein the silicates are selected from the group consisting of orthosilicate, sesquisilicate, metasilicate and silicate liquid consisting essentially of, adding to said detergents a boron containing compound selected from the group consisting of boric acid and alkali metal borates in at least a stoichiometric amount sufficient to convert the crystalline silicate to the disilicate when the mixture is dissolved in water.

2. The method of claim 1, wherein the silicate in the detergent composition has a Na_2O/SiO_2 ratio in the range of 2/1 to 1/2 and the boron containing compound is a sodium borate in the Na_2O/B_2O_3 range of 0/1 to 0.5/1.

3. The method of claim 1, wherein the boron containing compound is an alkali metal metaborate and sufficient acid phosphate salt selected from the group consisting of sodium dihydrogen phosphate and disodium phosphate is added to convert the metaborate to a Na_2O/B_2O_3 ratio in the range of 0/1 to 0.5/1.

4. A method of preventing silica bake-on deposits from mechanical dishwashing machine detergents comprising using a dishwashing composition consisting essentially of from 10-46 parts of a phosphate selected from the group consisting of sodium dihydrogen phosphate, disodium phosphate, trisodium phosphate and sodium tripolyphosphate, 22-36.8 parts of an alkali metal silicate selected from the group consisting of orthosilicate, sesquisilicate, metasilicate and silicate liquid and from 27-48.2 parts of a boron containing compound selected from the group consisting of boric acid and alkali metal borates, all of said parts being by weight of the composition.
